UNITED STATES PATENT OFFICE.

GEORGE W. MILLS, JR., OF BROOKLYN, NEW YORK.

NECKWEAR.

1,273,261.

Specification of Letters Patent.

Patented July 23, 1918.

Application filed March 18, 1915. Serial No. 15,178.

To all whom it may concern:

Be it known that I, GEORGE W. MILLS, Jr., a citizen of the United States, and a resident of the borough of Brooklyn, county of 5 Kings, and State of New York, have invented certain new and useful Improvements in Neckwear, of which the following is a specification.

My invention relates to neckwear, particularly of the kind in which the wearer forms the bow or knot, the invention being adapted for what are known as bow or string ties, four-in-hand ties of the different types, Ascot ties, etc. It has for its object 10 to provide neckwear in which the interlining is held against displacement and in which if the cover fabric is cut on the bias it is not liable to be stretched out of shape.

Heretofore, in scarfs of this type the neckwear fabric, that is, the silk cover fabric or fabric which is visible when the tie is in place, if cut on the bias, would stretch and lose its shape, would cord in the neckband portion, and the interlining would become 20 displaced. I have overcome these defects by my improved construction of neckwear, as hereinafter explained.

In the drawings, in which like letters refer to like parts, Figure 1 is the outer fabric or cover fabric of a necktie;

Fig. 2, a reinforcing or foundation fabric; Fig. 3, interlinings;

Fig. 4, shows the cover fabric, the reinforcing or foundation and interlinings assembled;

Fig. 5, shows a step in the formation of the completed tie;

Fig. 6, shows the inner face of the completed tie;

Fig. 7, shows a cross-section of the tie on lines 7-7, Fig. 4;

Fig. 8, is an enlarged cross-section on the lines 8-8 of Fig. 5;

Fig. 9, shows another form of tie embodying my invention;

Figs. 10 and 11 show my invention applied to a lined scarf; and

Fig. 11 being an enlarged cross-section of Fig. 10.

Referring to the drawings, A is the cover fabric, which is made of neckwear silks or neckwear fabrics, and as shown in Fig. 1, is preferably cut in two pieces connected by a seam A'. The cover fabric A I preferably 55 cut on the bias, as shown. B is what I have called a reinforcing or foundation fabric

and is preferably cut on the straight, and of a form similar, but not necessarily of the same size or shape, to a part of the cover fabric, as is more clearly shown in Fig. 2. 60 D, D, shown in Fig. 3, are interlinings for the tying ends of the tie, and they may be made separate or independent of each other as shown, or made separate and attached to the foundation, as shown in Fig. 4.

Having formed the cover fabric, as shown in Fig. 1, having cut the reinforcing or foundation fabric to the form desired, and the interlining for the tying ends, the interlinings are placed upon the reinforcing 70 or foundation fabric and stitched thereto by stitching E-E, extending lengthwise of the tying ends and across the inner ends of the interlinings. Of course, this stitching can be arranged to extend longitudinally as 75 shown. The interlinings having been attached to the reinforcing or foundation as shown in Figs. 4 and 9, the reinforcing or foundation B is laid upon the cover fabric A. The operator then stitches the foundation 80 B to the cover fabric A by rows of stitches C-C, preferably by machine. In the form of tie shown in Fig. 1, this row of stitches is preferably placed parallel to the edges of the interlining on both sides of the 85 interlining, the edge of the interlining acting as a guide for the operator, and the stitches are preferably placed a suitable distance away from the edge of the interlining on both sides thereof, so that when the edges 90 of the reinforcing or foundation fabric and the cover fabric are folded, the rows of stitches C will come on the inner face of the tie. I prefer to use a machine of the lock-stitch type for the stitches C-C.

In Figs. 1 and 4 I have shown where the cover and reinforcing or foundation fabrics are folded by the lines F-F, which, it will be readily seen, are between the stitches C and the edges of the interlining. While I have shown in the drawings a single row 100 of stitches C-C on each side of the interlining engaging with the reinforcing or foundation and the cover fabric to hold same together, or this stitching may be arranged in any suitable way for the purpose intended.

The next step in the method of manufacture of my invention is to fold the edges of the cover fabric and the reinforcing or 110 foundation so as to form the tie. This is done by folding the cover fabric and with

it the reinforcing or foundation fabric, as shown in Fig. 4, along the lines F—F. Having folded the fabrics and turned one of the edges under, as shown in Figs. 5 and 5 8, a row of either machine or hand stitching G is used to hold the same in position. The row of stitching I have shown in Fig. 8 is hand stitching and engaging with two plies of the cover fabric, two plies of the 10 reinforcing or foundation fabric and the interlining. In the manufacture of my improved scarfs, if desired, the stitches G need only engage the folds of the cover fabric, or the cover fabric and some of the other 15 plies. If desired, for the purpose of strength, machine stitches can be used to hold the adjoining edges of the cover fabric in engagement with each other.

In the drawings I have shown a form of 20 scarf having an anti-friction strip H, which is preferably made of a relatively smooth ribbon or similar material placed on the inner face of the neckband and held there by rows of stitching I. If desired, this could 25 be dispensed with and the cover fabric A extended over the inner face, either having the seam in the center of the neckband or having the cover fabric cut so that the 30 seam would be on one edge only of the neckband.

In Figs. 9, 10 and 11 I have shown my invention as applied to a lined scarf having the lining J. This lining J may be on the inner face of the tying ends only, as 35 shown in Fig. 10. In this form of scarf the cover fabric A is cut to the desired form, which may be the form shown in Fig. 9, or any other desired form, the cover and reinforcing or foundation fabric being cut to the 40 desired form and the interlining D cut to the desired form. The interlinings D are sewed to the reinforcing or foundation B by suitable stitches E, the reinforcing or foundation fabric sewed to the cover fabric 45 by suitable stitches C and the lining J sewed to the cover fabric A, by rows of stitches K. In Fig. 11, I have shown the rows of stitches K engaging only with the cover fabric and the lining. This form of tie 50 may also be manufactured by sewing the lining to the cover fabric by bringing the edges together and sewing them by machine stitches while the fabrics are turned wrong side out, and then reversing the 55 fabrics. This lined form of scarf embodying my invention may be made with the flowing ends as shown in Fig. 6, if desired, as well as the form shown in Fig. 10.

Having described my invention, what I 60 claim as new and desire to secure by Letters Patent is:—

1. A necktie having a neckband and a tying end, a piece of material folded to form both faces of said necktie, a foundation 65 fabric folded and positioned within and

completely inclosed by said piece of material and stitches engaging with said piece of material and said foundation fabric to hold same together along the longitudinal folded edges of said tying end. 70

2. In a necktie, a cover fabric, an interlining in a tying end thereof, a supplemental strip of material extending longitudinally of said tying end within said cover fabric and attached to said interlining 75 at or near the edge of said interlining and separate means attaching said strip to the cover fabric on the inner face of the tie at or near the longitudinal edge of said tying end. 80

3. A necktie having a neckband and a tying end, an outer piece of material forming both faces of said tying end of said necktie, a foundation fabric in said tying end of said tie and attached to said outer 85 piece, an interlining in said tying end attached to said foundation fabric, said foundation fabric being folded with and completely inclosed by a tying end portion of said outer piece of material, and a portion of said foundation fabric passing through the neck band of said tie and forming an interlining therefor. 90

4. A necktie having a neckband and two tying ends, an outer piece of material forming both faces of a tying end of said tie, a foundation fabric inclosed thereby, said foundation fabric being folded with said outer piece of material in a tying end of said necktie and extending in a single ply 100 only between the inner and outer faces of said neckband portion and stitching attaching said foundation and outer piece of material in a tying end so arranged as to be invisible on the front face of the tying end. 105

5. A necktie having a neckband and two tying ends, an outer piece of material forming both faces of a tying end of said tie, a foundation fabric inclosed thereby, said foundation fabric being folded with said outer piece of material in a tying end of said necktie and extending between the inner and outer faces of said neckband portion in a single ply only, a seam extending longitudinally of the tying end intermediate the edges thereof connecting said folded outer piece of material in place, and a seam on or near the edge of the neckband portion of said tie and stitching invisible on the front face of the tying end securing the said foundation fabric and outer piece of material together in said tying end. 115

6. A necktie having a neckband and two tying ends, a cover forming both faces of said necktie, a foundation fabric folded within and completely inclosed by said cover in a tying end of said tie and attached by stitching to said cover so that said stitching is invisible on the front face of the tying end, a single-ply portion only of said 120 125 130

foundation fabric passing through the neck-band of said tie. 1

7. In a necktie, a cover fabric, an interlining in a tying end thereof, a supplemental strip of material extending longitudinally of said tying end and attached to said interlining within said tying end and separate means attaching said strip to the cover fabric on the inner face of the tie at or near

10 the longitudinal edges of said tying end.

8. In a necktie, a cover fabric, a supplemental strip of foundation material extending longitudinally of a tying end of said tie, said strip being folded back with said cover fabric at the edges of said tying end, longitudinal rows of stitches attaching said folded back portions of said strip to the folded back portions of said cover fabric, substantially at the longitudinal edges of

20 said tie in said tying end.

9. In a necktie, a cover fabric, a supplemental strip of material extending longi-

tudinally of a tying end of said tie, said strip being folded back with said cover fabric at the edges of said tying end, longitudinal 25 rows of stitches attaching said folded back portions of said strip to the folded back portions of said cover fabric, substantially at the longitudinal edges of said tying end, an interlining in said tying 30 end and secured to said strip.

10. In a necktie, a cover fabric, an interlining in a tying end of said tie, a supplemental strip of material extending longitudinally of said tying end and being folded 35 longitudinally, means securing that part of said strip on one side of the fold to said interlining and means securing that part of said strip on the other side of the fold to said cover fabric. 40

In testimony whereof, I have signed my name to this specification.

GEO. W. MILLS, JR.
